POWER PLANE

Gus Heimsath, New Waterford, Ohio

Application June 6, 1935, Serial No. 25,329

1 Claim. (Cl. 145—5.1)

The present invention relates to new and useful improvements in power planes particularly for surfacing wood but it will be understood, of course, that a plane constructed in accordance with the present invention may be used for any purpose for which it may be found adapted and desirable.

An important object of the invention is to provide, in a power plane of the type including a plurality of rotary cutters driven by an electric motor, a novel construction, combination and arrangement of parts whereby said cutters and the motor may be expeditiously adjusted as a unit as desired.

Another very important object of the invention is to provide, in a power plane of the aforesaid character, novel means for automatically raising the cutters to inoperative or retracted position when the plane is raised out of engagement with the work on the return stroke or movement in a manner to prevent marking or spoiling said work.

Other objects of the invention are to provide a power plane of the aforesaid character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings, wherein like characters of reference designate corresponding parts throughout the several views, and wherein:—

Figure 1 is a view in vertical longitudinal section through a power plane constructed in accordance with the present invention.

Figure 2 is a view in bottom plan of the invention.

Figure 3 is a horizontal sectional view, taken substantially on the line 3—3 of Figure 1.

Figure 4 is a view in side elevation of the invention.

Figure 5 is a view in vertical transverse section, taken substantially on the line 5—5 of Figure 4.

Referring now to the drawings in detail, it will be seen that the embodiment of the invention which has been illustrated comprises a base 1 of suitable metal having formed integrally therewith upstanding side flanges 2. At an intermediate point, the base 1 is provided with a transverse opening 3 which extends upwardly in the side flanges 2, as illustrated to advantage in

Figures 2 and 4 of the drawings. Mounted on the forward portion of the base 1 is a handle 4.

Referring now to Figure 3 of the drawings, it will be seen that the side flanges 2 have formed thereon, adjacent the upwardly extending end 5 portions 5 of the opening 3, vertical guide ribs 6. Mounted for sliding adjustment on the guide ribs 6 between the side flanges 2 is a metallic frame 7 upon which an electric motor 8 is secured in a vertical position. It will be noted that the 10 sides of the frame 7 have channels formed therein which accommodate the guide ribs 6.

The frame 7 includes a pair of horizontally extending, vertically spaced flanges 9 through which the shaft 10 of the electric motor 8 rotatably extends. Also journaled in the flanges 9 on opposite sides of the motor shaft 10 are shafts 11 (see Figure 5). The shafts 11 are connected to the motor shaft 10 for rotation in unison therewith by gears 12 which are fixed on said 20 shafts between the flanges 9. Removably secured on the lower end portions of the shafts 10 and 11 for rotation in a horizontal plane are multiple bladed cutters 13. Of course, the cutters 13 are operable in the opening 3 for engagement 25 with the work. As indicated in Figure 2 of the drawings, the construction and arrangement of the members 13 is such that the cuts made thereby overlap. It will be noted that the upwardly 30 extending end portions 5 of the opening 3 accommodate the outermost gears 12 and the outer cutters 13. The reference numeral 14 designates a switch which is secured on the rear end portion of the base 1 for controlling the electric motor 8.

Extending slidably through the base 1, at a 35 point forwardly of the switch 14, is a vertical threaded post 15, as shown to advantage in Figure 1 of the drawings. The reference numeral 16 designates a lever which is pivotally mounted, at an intermediate point, on the base 1 between the 40 post 15 and the cutters 13. At its forward end, the lever 16 is operatively connected to the lowermost flange 9 of the frame 7, as at 17. At its rear end, the lever 16 terminates in a fork 18 which is engaged in an annular groove formed in the 45 lower portion of an adjusting nut 20 which is threaded on the post 15. The lower face of the base 1 has formed therein a recess or socket 21 for the reception of a substantially convex or rounded head 22 on the lower end of the 50 post 15. Mounted on the base 1 and rising therefrom is a housing 23 which encloses a coil spring 19 and through which the post 15 slidably extends. The coil spring 19 encircles the post 15 and has one end engaged with the top of the 55

housing 23 and its other end engaged with an abutment 25 on the post 15 for yieldingly urging said post downwardly.

It is thought that the operation of the invention will be readily apparent from a consideration of the foregoing, particularly to those skilled in the art to which said invention pertains. When the electric motor 8 is energized, the horizontally rotating, overlapping cutters 13, operating through the opening 3, impart to the work an exceedingly smooth surface as the device is moved thereover. When the plane is engaged with the work under the usual slight pressure the post 15 is forced upwardly against the tension of the spring 19 in a manner to positively project the cutters 13 through the opening 3 to cutting position. When the plane is lifted out of engagement with the work, as during the return stroke or movement, the spring 19 actuates the post 15 to lowered position, thus elevating the cutters 13 to retracted or inoperative position, as shown in Figure 1 of the drawings, for preventing marring of the work. Through the medium of the nut 20 the cutters 13 may be manually adjusted as desired. By substituting grinding wheels for the cutters 13 on the shafts 10 and 11 the tool may be successfully used on materials other than wood, such as metal, stone, concrete, etc., also for removing paint.

It is believed that the many advantages of a power plane constructed in accordance with the

present invention will be readily understood, and although a preferred embodiment of the invention is as illustrated and described, it is to be understood that changes in the details of construction and in the combination and arrangement of parts may be resorted to which will fall within the scope of the invention as claimed. 5

What is claimed is:—

A plane comprising a base having an opening therein and further having a socket therein, rotary cutters mounted for vertical movement of the base and engageable with the work through the opening, a housing mounted on the base, a vertical post extending slidably through the base and the housing, a substantially convex head on 15 the lower end of said post engageable with the work for elevating said post, the socket in the base being for the reception of said head, an adjusting nut threadedly mounted on the post, a lever pivotally mounted, at an intermediate point, on the base 20 and having one end operatively connected to the cutters and its other end operatively connected to the adjusting nut, said lever constituting means for connecting the cutters to the post and to the adjusting nut for raising and lowering said 25 cutters, and a spring in the housing operatively connected to the post for yieldingly urging said post downwardly for elevating the cutters when the plane is disengaged from the work.

GUS HEIMSATH.
